1

The present invention relates to the field of mass spectrometry. More particularly, the present invention is directed to a method and apparatus wherein ions obtained from a gasiform substance to be analyzed are formed into a pulsating beam.

The art of analyzing substances by means of a mass spectrometer is well known and comprises admitting the substance in the form of a gas under reduced pressure to a high vacuum tube wherein the gaseous material is bombarded with low energy electrons such that a small portion of the molecules are converted into ions of different masses. Each ion usually possesses a unit of positive electricity. The ions are forced into an accelerating field where they acquire equal kinetic energies and then pass into an analyzing portion of the mass spectrometer which usually comprises a curved conduit within an external magnetic field.

The ions moving at a high velocity through the analyzer portion of the mass spectrometer constitute an electric current and a magnetic field is produced simultaneously by the moving ions. An external, crossed magnetic field acts upon the magnetic field caused by the moving ions and causes the ions to be deflected in the curved conduit. The magnitude of the magnetic field and/or the magnitude of the accelerating voltage creating the accelerating field may be controlled such that ions of only one mass pass through an exit slit of the curved conduit of the analyzer and to the ion collecting means. The ions impinge on a Faraday cage or other collecting means which is grounded through a resistance and the neutralization of the charge carried by the ions causes a current to flow through the resistance and set up a potential drop. The potential drop is conventionally amplified in a D. C. amplifier and measured by means of a sensitive galvanometer or recorder. The current set up by neutralization of the ions impinging on the collecting plate is proportional to the number of ions striking the plate per unit of time. By proper manipulation of the external magnetic field and/or the accelerating electric field strengths, ions representing components of different molecular weights or masses can be caused to pass to the collector plate in sequence in order to obtain a record or a mass spectrum representing the composition of the substance.

In the conventional type of mass spectrometer, positive ions produced at the ion source are usually measured. Because of a small potential gradient maintained in the ion source, positive

2

ions are caused to pass into the ion accelerating field and are eventually passed through the analyzer portion of the mass spectrometer, whereas negative ions formed at the ion source are repelled and are thus prevented from passing to the accelerating field. Thus, the ions passing through the analyzer form a non-pulsating or steady positive ion beam which eventually impinges on the collector plate as mentioned above and are neutralized by a flow of electrons from ground. The electron flow is directly equivalent to the positive ion charge flow to the collector plate, and the

$$I \text{ (current)} \times R \text{ (resistance)} = E \text{ (voltage)}$$

difference across the ends of the grounded resistor is directly related to the current through the resistor. As previously mentioned, this current is related to the number of ions collected per unit time. Hence, the variations of the number of ions collected per unit time are converted into signals represented by voltage changes which are impressed on an electronic tube designed to amplify the magnitude of the original current to a magnitude amenable to standard measuring devices or recorders.

It is thus seen that direct currents set up by the neutralization of the direct positive ion beam on the collector plate are amplified and measured in the conventional equipment. Direct current amplification of the voltage change, however, has certain drawbacks. It is known, for example, that A. C. amplifiers are inherently more stable than D. C. amplifiers. Direct current amplifiers also are subject to what is known as "zero drift" resulting from the fact that aging of filament, minute changes of potentials within the electronic tubes, and similar disturbances upset the balance of conditions previously established causing a new set of operating parameters to exist. These new parameters obviously produce a shift of the apparent balance which is interpreted as a "zero drift." A. C. amplifiers respond only to signals of periodic character and have no output for no input signal; hence, in the quiescent period, no output is obtained which means that no shift of balance can appear. Direct current amplifiers are also known to have less usable sensitivity and to respond more slowly to voltage fluctuations than do A. C. amplifiers. It would, therefore, be extremely desirable to have available a means for using A. C. amplification of the ion beam currents in order to eliminate the aforementioned difficulties. The present invention is directed to a novel means of forming a pulsating ion beam

signal amenable to amplification in an A. C. amplifier.

It is the principal object of my invention to provide a means for improving the operation of a mass spectrometer.

It is another object of the present invention to provide a magnetic means for modulating a non-pulsating ion beam such that a pulsating ion beam signal is formed.

It is a further object of the present invention to improve the stability and sensitivity of a mass spectrometer with respect to the amplification and recording of signals produced subsequent to the collection of ion beams of various masses.

Briefly, the present invention involves bombarding a gasiform material with an electron beam such that ions of various masses are formed, passing the ions through an analyzer portion of a mass spectrometer to segregate an ion beam comprising ions of one particular mass, said ion beam being direct or non-pulsating in character, subjecting the direct ion beam to a magnetic field periodic in character and of one polarity or of constantly changing polarity such that the ion beam is periodically deflected away from a collecting means or is periodically deflected from one to another of a plurality of collecting means, collecting the pulsating signal or signals thus produced in the ion collecting means and amplifying the pulsating signal or signals in an A. C. amplifier which may be tuned to the frequency of the periodic deflections imposed on the steady ion beam by the magnetic field.

The present invention takes advantage of the fact that the steady ion beam comprising ions of any one mass leaving the analyzer portion of the mass spectrometer constitutes an electric current which produces a magnetic field. By subjecting the magnetic field produced by the moving ions to an auxiliary magnetic field periodic in character and of one polarity or to a magnetic field of constantly changing polarity, it is possible to deflect alternately the ion beam from the collecting portion of a mass spectrometer such that only a portion of the ions reach the collecting means and, consequently, only a portion of the ions are periodically neutralized by a flow of current from the grounded resistance attached to the collecting means. The periodic flow of neutralizing current results in the formation of a pulsating signal which is amenable to amplification in an A. C. amplifier. Likewise, by providing the collecting portion of a mass spectrometer with a plurality of collecting means electrically connected through separate channels to a "push-pull" A. C. amplifier, the ion beam may be deflected from one collecting means to another alternately by means of a magnetic field of constantly changing polarity which results in producing two pulsating signals which may be amplified and subsequently combined for use as a means of indicating the relative abundance of ions of any one mass in the original ion beam. The practice of the present invention is useful in that no matter what types of collecting means are employed, the principle is employed in which a magnetic field, periodic in character, alters the course of the non-pulsating ion beam to produce a pulsating signal which is a function of the number of ions collected per unit time. The pulsating signal is more easily controlled and amplified than non-pulsating signals produced in conventional mass spectrometers.

Several embodiments of the device of the present invention will now be described in detail in conjunction with the accompanying drawings in which

Figure 1 is an elevation, partly in section, with conventional electric units comprising a side view of the assembly along with conventional symbols.

Figure 2 is a side view of the collecting portion of the mass spectrometer assembly shown in Figure 1.

Figure 3 shows an end view of the collecting portion of the mass spectrometer, shown in Figure 1.

Figure 4 shows a side view of another embodiment of the collection portion of a mass spectrometer.

Figure 5 shows the geometrical relationship between the various elements of the collection portion of the mass spectrometer illustrated in Figure 2, and

Figure 6 shows the geometrical relationship of the various elements of the collection portion of the mass spectrometer illustrated in Figure 4.

Turning now to Figure 1, the numeral 11 designates the ionization chamber of a mass spectrometer, numeral 12 designates the analyzer portion of the mass spectrometer and numeral 13 designates the collection portion of the mass spectrometer tube. The particular tube shown is of the 90° type frequently used in the analysis of gaseous mixtures. My invention is not limited, however, to any specific type of mass spectrometer tube but is applicable to analysis of gasiform material in the horizontal, 60°, 180° and other types of mass spectrometer tubes.

The mass spectrometer tube may be constructed of glass and is connected to a sample system 14 containing drawout electrode 15. The tube also is connected to a vacuum pump system 16 which maintains the entire system under an extremely low pressure such as from 10^{-3} to 10^{-6} millimeters of mercury, absolute pressure, and withdraws from the tube unreacted portions of the gasiform material introduced therein. The ionization chamber 11 of the mass spectrometer tube also contains filament 17, made of tungsten or other such material, which is connected to an electronically regulated power supply, not shown. Also contained in the ionization chamber are electrodes 18 and 19 containing aligned slits 20 and 21, respectively, and electron collector electrode 22. Electrodes 23 and 24 placed directly under drawout electrode 15 contain aligned slits 25 and 26, respectively, these two electrodes conveniently being termed the ion source of the mass spectrometer.

The analyzer portion 12 of the mass spectrometer tube contains two electrodes 27 and 28 placed at opposite ends of the curved conduit and containing slits 29 and 30, respectively. The analyzer electrodes are connected through an internal non-magnetic shield 31. The curved portion of the mass spectrometer is surrounded by an external crossed magnetic field 32, which is produced by a suitable electromagnet 33, the magnitude of which is controlled by a power supply, not shown. The ion collection portion of the mass spectrometer tube 13 comprises the decelerating field made up of electrode 34 containing slit 35 and shielding electrode 36 containing slit 37 and the collecting electrode 38. Electrode 38 is connected through lead 39 to grounded resistance 40 and A. C. amplifier 41. The A. C. amplifier is connected through suitable leads represented by numeral 42 to a rectifier system 43 which, in turn, is electrically con-

nected through lead 44 to a galvanometer or recorder system 45.

The numerals 46 and 46' represent the poles of an external magnet for producing a transverse magnetic field for the collection portion of the mass spectrometer tube. This magnetic field, which will be referred to by the numeral 46, will be described in more detail hereinafter. In Figure 1, it is noted that ion source electrodes 23 and 24 are connected through leads 47, 48 and 49 to ground and that analyzer electrodes 27 and 28 are connected through leads 50 and 51 to a source of high potential at junction 52. Drawout electrode 15 is connected to a source of potential by means, not shown, the magnitude of which is slightly higher than the magnitude of the potential impressed on electrodes 23 and 24.

Figure 2 illustrates a side view of the collection portion of the mass spectrometer tube, showing electrodes 34 and 36 and collector electrode 38. The poles of the electromagnet represented by the numerals 46 and 46' are connected to a suitable electromagnet 53.

Figure 3 shows the end view of the collecting portion of the mass spectrometer, the numeral 13 designating the mass spectrometer tube itself, the numerals 46 and 46' representing the poles of the magnet and the numeral 53 showing the electromagnet supplying energy to the poles 46 and 46'. Current for magnet 53 is supplied through lead 54 electrically connected to oscillator 55 and lead 56 containing resistor 57 which is electrically connected through lead 58 to oscillator 55. Oscillator 55 determines the frequency of the changes of polarity in electromagnet 53. A suitable voltage regulator may also be incorporated in the system if desired to regulate the current for the electromagnet.

Figure 4 shows a side view of another embodiment of the collecting portion of the mass spectrometer tube, partly in section, which contains analyzer electrode 28, decelerating electrode 34, shielding electrode 36 and two collecting electrodes 59 and 60, respectively. Electrode 59 is electrically connected through lead 61 to grounded resistor 62 and to one channel of "push-pull" A. C. amplifier 63. Electrode 60 is likewise connected through lead 64 to grounded resistor 65 and to the other channel of "push-pull" A. C. amplifier 63.

Returning now to Figure 1, the operation of the mass spectrometer will be described in more detail. A small amount of gasiform substance to be analyzed is introduced from drawout electrode 15 into the dissociation region existing between electrodes 18 and 19. An electron beam 66 originating from heated filament 17 flows in a path perpendicular to the flow of the gas from electrode 15, this electron beam being maintained in a horizontal flat ribbon through the dissociation region by means of an externally applied magnetic field, not shown, such that electrons impinge on electron collector 22. A portion of gaseous molecules entering the dissociation region are bombarded by the electrons and form ions of various masses. A small potential difference of proper polarity is maintained between drawout electrode 15 and electrode 23 such that ions (either positive or negative) are slowly moved towards accelerating field entrance slit 25 in electrode 23. The ions then pass through focusing electrode slit 26 and are accelerated in the field existing between electrodes 24 and 27 due to the large potential difference existing between these two electrodes.

A portion of the ions then passes through analyzer entrance slit 29 and into magnetic field 32. By controlling the magnitude of magnetic field 32 and/or the strength of the accelerating field 5 existing between electrodes 24 and 27, ions of any one selected mass may be made to focus on analyzer exit slit 30, the remainder of the ions impinge on shield 31 whereon they are neutralized and pumped out of the system by means of vacuum pump 16. The ions focused on exit slit 30 designated by the numeral 67 constitute ions of any one mass in a steady or direct beam. The ion beam 67 then enters the decelerating portion of the collector end of the mass spectrometer tube, the decelerating field existing between electrode 28 and grounded electrodes 34 and 36. Since electrodes 34 and 36 are maintained at substantially the same potential as electrodes 23 and 24, the ions are slowed down in velocity to the same extent that they were speeded up in accelerating field existing between electrodes 24 and 27. The ion beam reaching electrode 38 is, therefore, slowed down to a few volts energy approximately being equivalent to the potential difference between drawout electrode 15 and electrodes 23 and 24.

Ion beam 67 is subjected to magnetic field 68 of periodically changing polarity such that only a portion of the ions impinge on collector plate 38. The method of deflecting the ion beam off and on the plate 38 will be described in more detail hereinafter. The portion of ions impinging on collector plate 38 is neutralized by a flow of current received from ground which flows through resistor 49 to the collector plate. The neutralization of the charge carried by the ions set up a potential drop which is applied to A. C. amplifier 41 containing amplifier tubes such as 68. The signal formed at collector plate 38 and resistor 49 is periodic in character, A. C. amplifier 41, which may be tuned to the deflecting frequency imposed on ion beam 67, will amplify the signal, rectifier 43 will change the amplified A. C. signal into a D. C. signal which may be recorded by conventional methods in recorder 45.

Turning now to Figure 2, it is seen that ion beam 67 passing in the magnetic field 46 is alternately deflected from one side of collector plate 38 to the other. Magnetic field 46 of constantly changing polarity has a strength just sufficient to cause ion beam 67 to be deflected from either side of the collector plate, the portion of the ion beam sweeping across the collector plate being neutralized by a flow of current through the grounded resistance as hereinbefore described and the portion of the ions deflected off of the collector plate impinging on a suitable internal shield within collecting means 13 and being neutralized and pumped out of the system.

Turning now to Figure 3, the method of controlling the polarity and strength of magnetic field 46 is shown. Voltage is supplied to oscillator 55 through leads 69 and 70, oscillator 55 controlling the frequency of the polarity change of the magnetic field. Oscillator 55 is directly connected through lead 54 to electromagnet 53 and indirectly through resistor 57 and lead 56. By changing resistor 57, it is possible to change the strength of the magnetic field of poles 46 and 46'.

The operation of the collection portion of a mass spectrometer shown in Figure 4 is similar to that previously described. Collecting electrodes 59 and 60 having equal areas are separated by a very small space and the strength of

magnetic field 46 is adjusted such that ion beams 67 will be alternately deflected from one collector plate to the other. During any portion of the time that the ion beam is on one or the other collector plate, the ions are neutralized and a potential drop is set up with the grounded resistance connected to each collector plate. During the portion of the time that the ion beam is passing from one collector plate to the other, it impinges on an internal shield, not shown, which may suitably be placed behind the collector plates and the ions are neutralized and pumped out of the system. Therefore, two pulsating signals are set up in leads 61 and 64, each being carried to its respective channel in a conventional "push-pull" A. C. amplifier 63. The separate signals may subsequently be combined, rectified, and recorded.

Turning now to Figure 5, the mathematical derivation of the magnetic field strengths of alternating polarity required to deflect an ion beam from a single electrode will be discussed in detail. When the axis of the external coil magnetic system is perpendicular to the axis of the ion collector system, a magnetic field perpendicular to the path of ion beam 67 may be determined by the following equation:

Equation 1

$$Hev = \frac{mv^2}{r}$$

where H =magnetic field strength in oersteds, e =charge in E. M. U. (electromagnetic units) on m =mass having v =velocity and r =radius of circle of resulting path.

It is seen that for any one mass, e , v , and m are constant; therefore, the curvature of the path,

$$P = \frac{1}{r}$$

is proportional to H , the magnetic field strength.

Equation 1 may be suitably written in terms of voltages by use of the following equation:

Equation 2

$$Ve \cdot 10^8 = \frac{1}{2} mv^2$$

where V =accelerating voltage, e =charge in E. M. U. on m =mass of particle, where v =velocity resulting therefrom.

By combining Equations 1 and 2, the following is obtained:

Equation 3

$$\frac{H^2 er^2}{m} = 2V \cdot 10^8$$

and when m_H =mass hydrogen and M =mass number, Equation 3 becomes:

Equation 4

$$\frac{H^2 e}{m_H} r^2 = 2MV \cdot 10^8$$

It is seen that the magnitude of H may be suitably adjusted to control the extent to which ions of any one mass are deflected. Use may be made of Equation 4 to determine the minimum H necessary to deflect ions having a mass 100 away from a collector electrode having a diameter of 0.6 centimeter. In Figure 5, it is seen that a magnetic field H has been imposed on ion beam 67 causing the ion beam to have a radius of curvature r and to be deflected the distance x causing it to miss the collector electrode 38. D repre-

sents the horizontal distance through which field H acts on the ion beam. By using the principle of similar triangles, the following approximate relation is obtained:

$$\frac{x}{D/2} = \frac{D}{r-x}$$

therefore

$$r = \frac{D^2}{2x} + x$$

and since x is approximately equal to

$$r = \frac{D^2}{d} + \frac{d}{2}$$

which, when substituted into Equation 4, gives:

Equation 5

$$H = \sqrt{\frac{2MV \cdot 10^8}{e/m_H} \cdot \frac{1}{\left(\frac{D^2}{d} + \frac{d}{2}\right)}}$$

where H is the minimum magnetic field strength to cause the ion beam to be deflected off of the collector plate. When $M=100$ mass number, $V=16$ volts, $e/m_H=0.96 \times 10^4$ E. M. U./gram, $D=2$ centimeters, and

$$\frac{d}{2} = 0.1 \text{ centimeter}$$

the minimum H as determined from Equation 5 is:

$$H \approx 210 \text{ oersteds}$$

If a smaller collector plate is used than is shown above, the H may be decreased. Specifically, for a collector plate having a radius of 0.7 mm., $H=80$ oersteds. Obviously, for ions having masses below 100, the magnetic field strength requirements will be lower than those shown above.

Turning now to Figure 6, a different situation is obtained to that previously described in conjunction with Figure 5; that is, the ion beam is deflected from one of a plurality of collector plates to another. The distance d in this case is the space between electrodes 59 and 60 and x is the distance the magnetic field H deflects the ion beam from its usual path to cause impingement on one of the electrodes. It is readily seen that if $x=\frac{1}{2}d$, one obtains the minimum distance the ion beam must travel to contact one of the electrodes. By employing the reasoning used in connection with Figure 5, and assuming that $d=0.02$ cm. with other values the same as previously used substituted in Equation 5, $H \approx 22$ oersteds or less.

It is seen from the foregoing discussion that the magnetic fields required to produce deflection of ions having masses as high as 100 are easily produced with currents available from conventional electronic apparatus. Since the frequency of the deflecting magnetic field imposed on the ion beam controls the wave form of the resulting signal produced, it is possible to tune the particular type of A. C. amplifier used to the interruption frequency to amplify the pulsating signal. The method of the present invention is effective in that the magnitude of the collecting currents are very easily controlled. Suitable magnetic field strengths may be employed which will cause the ion beam to avoid the collector plate over any

portion of the modulation cycle; that is the pulse to signal ratio may be varied from

$$1 > \frac{\text{pulse time}}{\text{cycle time}} > 0$$

The system illustrated in Figure 4 is more effective than the system illustrated in Figures 1 and 2 in that a greater portion of the energy of the ion beam in the system is utilized than in the latter system. This is because a smaller quantity of the ion beam is deflected from the collector plates when using two or more collector plates than is the case when using only one collector plate.

The magnetic field employed to deflect the ion beam from the collector plate, when employing only one collector plate, may be of any one polarity but made periodic in character by periodically interrupting the direct current to the magnet. In other words, only one polarity of the magnet is required in which the axis of the external coil system is placed perpendicular to the axis of the ion collector system such that the magnetic field is perpendicular to the path of the ions. By employing the magnetic field in this manner, the ion beam may be deflected from the center portion of the collector electrode to just beyond one end of the electrode which sets up pulsating signals amenable to amplification in an A. C. amplifier.

When employing two or more collector electrodes, it is preferred to change the polarity of the magnetic field while making the change periodic in character such that the ion beam may be deflected in two different directions as previously described. Regardless of whether the periodically varying magnetic field is of constantly changing polarity or of one polarity and periodic in character, the pole pieces or coils producing the field should be of such size as to cause deflection of the ion beam without either affecting the focusing of the ion beam or changing the character of the signal resulting from the collected ion beam. The rate at which the magnetic field deflecting the ion beam is varied will depend to a large extent on the type of A. C. amplifier employed. Signals pulsating at a rate of from about 60 to 300 cycles per second are generally preferred; however, the deflecting magnetic field may be varied to produce signals pulsating at lower or higher rates than the range heretofore mentioned under certain conditions.

Another method of carrying out the deflecting system comprises employing shielding electrode 36 as the means for cutting off the deflected ion beam. For example, in Figure 2 the slit 37 in shielding electrode 36 may be made of such size that, as the ion beam is deflected in one direction, the beam will contact a portion of the electrode and the ions will be neutralized. When the magnetic field changes in polarity, the ions are deflected across the collector electrode in another direction and are interrupted by another portion of the shielding electrode 36. There are other methods of cutting off the deflected ion beam which may be preferred under some circumstances, but it is to be understood that any method of employing a magnetic field to obtain the desired deflection of the ion beam is within the scope of the present invention.

In the description of the present invention, I have shown the method of carrying out the magnetic modulation of the ion beam in which the ion source comprises electrodes 23 and 24 and grounded and analyzer electrodes 27 and 28 are at high potential while electrodes in the collect-

ing portion of the mass spectrometer are maintained at substantially ground potential. It is usually preferred to carry out the magnetic modulation procedure with the ion source at ground potential because, as previously pointed out, the ion beam is decelerated under such conditions in the collecting portion of the mass spectrometer to very low velocities and low energies. Hence, the strength of magnetic field 46 required to deflect the ion beams from the collector plates will be relatively small as compared to the strength of the magnetic field that would be required if the ion source were at high potential and the ion beam passing to the collecting plate had extremely high velocities and high energies.

It is also obvious to one skilled in the art that for ions of any given mass, a specific magnetic field strength will be required to deflect the ions from a collector plate of a given size. As ions of various masses are focused on the collector system, it may be necessary to change the strength of magnetic field 46 in order to obtain the desired deflection of the ion beam. In order to accomplish a change of the collector magnetic field strength, it may be desired to coordinate changes in resistance 57 shown in Figure 3 with any change imposed on the magnetic field 32 or the accelerating potential imposed at junction 52 shown in Figure 1 when various ion masses are being analyzed. It may not be necessary under some circumstances to change the strength of magnetic field 46 each time a different mass is focused on exit slit 38, particularly if the slit opening 37 in shielding electrode 36 is of such size that the ion beam may be cut off by this electrode when it is deflected from one portion of collecting electrode 33 to another portion of this electrode. When analyzing for masses ranging from 2 to 25, approximately the same magnetic field 46 may be employed for any particular mass. In the range of masses from 25 to 50, the strength of the magnetic field 46 may be changed in order to obtain the desired deflection of the ion beam. Similarly, for masses ranging from 50 to 100 another change may be made on the magnetic field 46 to obtain the desired deflection of ion beam.

It is to be understood that the present invention is applicable to the analysis of an ion beam comprising negative ions as well as positive ions. If it is desired to analyze for negative ions, proper changes must be made throughout the mass spectrometer with respect to polarity in order that only negative ions formed by bombardment of gasiform material with electrons are accelerated through the analyzer portion of the mass spectrometer.

The method and apparatus described in the present invention is applicable for testing a wide variety of solid, liquid or gaseous substances. The procedure is only limited in that the substance be vaporizable under the low pressure conditions existing in the mass spectrometer.

The nature and objects of the present invention having been fully described and illustrated, what I wish to claim as new and useful and to secure by Letters Patent is:

1. In a mass spectrometer including a means for focusing a non-pulsating beam of ions having a selected mass on a collecting means, means for producing a periodically varying transverse magnetic field following said focusing means and ahead of said collecting means whereby said beam is periodically deflected from said collecting means.

11

2. In a mass spectrometer including means for producing a non-pulsating beam of ions of a particular mass, means for collecting said beam and means for focusing said beam on said collecting means, the improvement which comprises means for producing a periodically varying transverse magnetic field arranged following said focusing means and ahead of said collecting means whereby said non-pulsating beam is periodically deflected from said collecting means.

3. A mass spectrometer including a means for forming a beam of ions having a selected mass which comprises, in combination, a plurality of ion collecting means, amplifying means electrically connected to each of said collecting means, means for producing a periodically varying transverse magnetic field arranged external to and in front of said collecting means whereby said beam of ions is periodically deflected from one to another of said plurality of collecting means.

4. A mass spectrometer apparatus including means for forming a homogeneous beam of ions corresponding to a selected mass, means for focusing said homogeneous beam upon ion collecting means, a collecting means comprising a pair of ion collecting members arranged adjacent each other and spaced on opposite sides of the focus path of said beam, means for producing a periodically varying transverse magnetic field arranged external to and spaced in front of said collecting means whereby said focused beam is periodically deflected from one to the other of said pair of collecting members, and a push-pull amplifying means having the input terminals thereof electrically connected in shunt to said collecting members.

5. In a method for operating a mass spectrometer wherein a beam of ions corresponding to a selected mass is formed and is focused upon a collecting member to produce an electric signal, the improvement which comprises subjecting the focused beam of ions to a transverse field force of periodically changing polarity and of such strength that said focused beam is periodically deflected from said collecting member, and col-

10
15

lecting a portion of the resulting deflected ion beam whereby a pulsating electric signal is produced.

6. In a method for operating a mass spectrometer having a collecting means, including at least one ion collecting member, and having means for focusing a beam of ions corresponding to a selected mass upon said collecting means to produce an electric signal, the improvement which comprises the steps of subjecting the focused ion beam to a transverse magnetic field of periodically changing polarity and of such strength that the ion beam is periodically deflected off of said collecting member, collecting a portion of the resulting deflected ion beam whereby a pulsating electric signal is produced, and amplifying said pulsating electric signal.

7. In a method for operating a mass spectrometer having a collecting means, including a space pair of collecting members, and having means for focusing a beam of ions corresponding to a selected mass upon said collecting means to produce an electric signal, the improvement which comprises the steps of subjecting the focused ion beam to a transverse magnetic field of periodically changing polarity and of such strength that the ion beam is periodically deflected from one collecting member, to the other of said pair, collecting portions of the resulting deflected ion beam whereby a pulsating electric signal is produced, and amplifying said pulsating electric signal.
